UNITED STATES PATENT OFFICE.

JOSEPH SCHMALZL, OF SOUTH BETHLEHEM, PENNSYLVANIA.

ROCKING-CHAIR FAN.

1,273,097.

Specification of Letters Patent. Patented July 16, 1918.

Application filed March 10, 1917, Serial No. 153,884. Renewed June 10, 1918. Serial No. 239,289.

To all whom it may concern:

Be it known that I, JOSEPH SCHMALZL, a citizen of the United States, residing at South Bethlehem, in the county of Northampton and State of Pennsylvania, have invented a new and useful Rocking-Chair Fan, of which the following is a specification.

The device forming the subject matter of this application is a means whereby rotation may be imparted to a fan, by the movement of a rocking chair.

The invention aims to provide novel means whereby motion may be transmitted from the chair to the fan.

Another object of the invention is to provide novel means for assembling the chair with the base which carries the fan.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 is an elevation showing the device forming the subject matter of this application in connection with a rocking chair;

Fig. 2 is a fragmental sectional view showing the weight whereby the base is held in place;

Fig. 3 is a fragmental sectional view showing the screw whereby the base is held in place;

Fig. 4 is a top plan of the structure shown in Fig. 3;

Fig. 5 is a cross section taken approximately on the line 5—5 of Fig. 1;

Fig. 6 is a longitudinal section of the standard which carries the fan and the mechanism for actuating the fan;

Fig. 7 is a section taken approximately on the line 7—7 of Fig. 5;

Fig. 8 is a perspective view showing a keeper which is applied to the rocker of the chair;

Fig. 9 is a perspective view showing the

bearing which is located at the upper end of the standard; and

Fig. 10 is a perspective view showing an element which co-operates with the structure delineated in Fig. 9.

In the accompanying drawings, the numeral 1 indicates a base which may be in the form of a flat board. In Fig. 3, the numeral 2 designates the floor on which the base 1 rests. Any means may be provided for securing the base 1 to the floor 2. The base 1 may be supplied with a hole 3 in which is mounted a bushing 4 having a flange overlapping the upper face of the base 1, securing elements 6 passing through the flange 5 to hold the bushing on the base. Threaded into the bushing 4 is a screw 7 which is adapted to engage the floor 2, in order to hold the base against movement thereon. The screw 7 has a turning head 8. In case 75 it is desired that the floor 2 shall not be marred, then a weight 9 may be placed on the base 1 at one corner thereof or elsewhere, the weight 9 being shaped as shown at 10, to conform to the outline of the corner of 80 the base 1. The weight 9 is supplied with a lifting eye 11 and has seats 12 in its lower face, adapted to receive pins 14 projecting upwardly from the base 1, the construction being such that although the weight 9 may 85 be lifted readily off the base 1, the weight will not shuck or move about on the base. One edge of the base 1 carries a track 15 which may be in the form of an angle member including a vertical flange 16 and a horizontal flange 17, the horizontal flange 17 being attached to the bottom of the base 1 by means of securing elements 18.

In the upper face of the base 1 there is fashioned a recess 19 which may be located 95 adjacent the geometrical center of the base. Mounted in the bottom of the recess 19 is a resilient buffer 20. Surrounding the recess 19 and disposed on the upper face of the base 1 is a foot plate 21 held in place by 100 securing elements 22 and including a neck 23 into which the lower end of the tubular standard 24 is threaded, the standard abutting against the buffer 20. Since the buffer 20 is resilient, one purpose of the buffer is 105 to prevent the standard 24 from rotating in the neck 23, when the lower end of the standard 24 is firmly seated on the buffer. The tubular standard 24 terminates at its upper end, as shown in Fig. 9, in parallel, vertical 110

side plates 25 having openings 26. In the upper edges of the side plates 25, notches 27 are formed, the same defining long arms 28 and short arms 29. The arms 28 are connected by a guide pin 30. Applied to the outer faces of the side plates 25 are disks 31 having openings 33. Securing elements 32 are mounted in the openings 33 of the disks 31 and in the openings 26 of the side plates 10 25, to hold the disks in place on the side plates. The disks 31 are supplied with inwardly projecting tubular bearings 34, having parallel-sided recesses 35 which, coöperating with the inner edges of the arms 28 15 and 29, prevent the bearings from rotating. Journaled for rotation in the bearings 34 is a shaft 36 to the intermediate portion of which is secured a sheave 37. The inner ends of the bearings 34 engage opposite faces 20 of the sheave 37, and thus the shaft 36 is prevented from moving endwise. Mounted on one end of the shaft 36 is a fan 38 mounted in place by nuts 39.

A weight 40 is mounted to reciprocate in 25 the tubular standard 24. At its ends, the weight 40 is surrounded by resilient bands 41. The bands prevent the weight 40 from making a noise, when the weight moves vertically in the standard 24. The weight 40 30 is provided at its lower end with a reduced tip 42 which, engaging the resilient buffer 20, prevents noise when the weight 40 moves downwardly to an extreme position. In the upper end of the weight 40 there is fashioned 35 a bore 43, communicating with a cross passage 44. The lower end of a flexible element 45 extends downwardly into the bore 43 and is provided with a knot 46 or other projection, so that the flexible element 45 40 cannot be pulled out of the bore 43. In practical operation, the lower end of the flexible element 45 may be pushed downwardly through the bore 43 and outwardly in a lateral direction through either end of the passage 44. The knot 46 then is formed, and finally the flexible element 45 is drawn up 45 into the position shown in Fig. 6.

The numeral 47 denotes a chair including 50 a rocker 48. The rocker 48 is received between the vertical flange 16 of the track 15 and the adjacent edge of the base 1, and is mounted to oscillate on the horizontal flange 17 of the track. The chair 47 includes a back post 49. The flexible element 45 extends upwardly across the sheave 37, and beneath the guide pin 30, the upper end of the flexible element being fashioned into a loop 50 which is slipped over the upper end of the back post 49, as clearly shown in Fig. 6. Secured to the inner face of the rocker 48 is a keeper 51 having, as shown in Fig. 8, an intermediate offset portion 52, in the lower edge of which a notch 53 is formed. The numeral 54 denotes a helical spring disposed above the base 1. One end of the

spring 54 is bound beneath a plate 55 held by securing elements 56 to the base 1. Mounted in the spring 54 is a rod 57 which serves to give a stiffness to the spring. The numeral 58 denotes a button having a stem 70 59, provided with projections 60, engaging certain of the outer convolutions of the spring 54.

In practical operation, the rocker 48 is seated in the track 15 as shown in Fig. 7. 75 The button 58 is engaged within the part 52 of the keeper 51, the neck or stem 59 of the button being received in the notch 53. In this way, the rocker 48 is so connected with the track 15 that the rocker will not 80 creep out of the track when the rocker is oscillated. The spring 54 tends to swing the button 58 upwardly, and consequently the button is firmly maintained in engagement with the part 52 of the keeper 51. If, 85 however, the operator wishes to disengage the button 58 from the keeper 51, it may be brought about readily by pressing the spring 51 downwardly with the foot. The rod 57 inside of the spring 54 gives the spring the 90 necessary stiffness.

When the rocking chair 47 is swung to and fro, the flexible element 45 will be reciprocated. When the flexible element 45 is advanced, the shaft 36 and consequently 95 the fan 38 will be rotated, because the flexible element bears frictionally on the sheave 37. When the flexible element 45 is advanced, the weight 40 is elevated, the weight constituting a means for retracting 100 the flexible element. The fan 38, the shaft 36 and the sheave 37 are sufficiently heavy so that the backward dragging action of the flexible element 45 on the sheave 47 will not appreciably retard the rotation which 105 has been imparted to the fan 38 when the flexible element 45 is advanced, and when the weight 40 is lifted. The bands 41, co-acting with the standard 24, retard the downward movement of the weight 40, so 110 that the flexible element 45 will slacken up slightly, when the chair is swung forwardly, thereby permitting a continuous rotation of the fan 38 in one direction, as above stated. 115

As hereinbefore stated, the resilient bands 41 on the weight 40, taken in connection with the buffer 20, will cause the structure to work noiselessly, a condition desirable if not absolutely necessary in structures of 120 this kind.

If desired, the tubular standard 24 may be supplied with brackets 70 supporting a shelf 71 on which refreshments, books and other articles may be placed. 125

Having thus described the invention, what is claimed is:

1. In a device of the class described, a base; a tubular standard carried by the base; a shaft journaled for rotation in the upper 130

- end of the standard; a fan carried by the shaft; a sheave carried by the shaft; a weight mounted to reciprocate in the standard; a flexible element connected with the 5 weight and trained across the sheave; a track carried by the base; a chair including a rocker mounted to move on the track, the flexible element being connected with the chair; a keeper carried by the rocker and 10 provided with a notch in its lower edge; and a spring one end of which is secured to the base, the other end of the spring being provided with a button received in the notch, the spring exerting an upward 15 pressure on the button, to maintain the button firmly engaged in the notch.
2. In a device of the class described, a base provided with a recess; a resilient buffer seated in the recess; a tubular stand- 20 ard mounted in the recess and abutting at its lower end against the buffer; a weight mounted to reciprocate in the standard; a resilient band surrounding the weight and coacting with the bore of the standard, the 25 band and the buffer coöperating to reduce the noise incident to the reciprocation of the
- weight in the standard; a shaft journaled for rotation in the upper end of the stand- 30 ard; a sheave carried by the shaft, the flexible element being trained across the sheave; and a fan carried by the shaft.
3. In a device of the class described, a base; a tubular standard carried by the base; a shaft journaled for rotation in the upper end of the standard; a fan carried by 35 the shaft; a sheave carried by the shaft; a weight mounted to reciprocate in the standard; a friction element carried by the weight and coacting with the standard to retard the downward movement of the 40 weight; a flexible element connected to the weight and engaging a part of the periphery of the sheave; and a rocking chair whereunto the flexible element is connected. 45

In testimony that I claim the foregoing 45 as my own, I have hereto affixed my signature in the presence of two witnesses.

JOSEPH SCHMALZL.
